PATENTED NOV. 28, 1905.

F. P. HUMMEL.
INSTANTANEOUS STEAM GENERATOR.

APPLICATION FILED DEC. 22, 1904.

2 SHEETS—SHEET 2.

UNITED STATES PATENT OFFICE.

FRANKLIN PIERCE HUMMEL, OF BELLEVUE, OHIO

INSTANTANEOUS STEAM-GENERATOR.

No. 805,961.

Specification of Letters Patent.

Patented Nov. 28, 1905.

Application filed December 22, 1904. Serial No. 237,978.

To all whom it may concern:

Be it known that I, FRANKLIN PIERCE HUMMEL, a citizen of the United States, residing at Bellevue, in the county of Huron and State 5 of Ohio, have invented a new and useful Instantaneous Steam-Generator, of which the following is a specification.

This invention relates to that class of steam-generators in which the feed-water is practically instantaneously vaporized or converted into steam and which are commonly known as "flashers," the object of the invention being to simplify and improve the construction and operation of this class of devices.

With these and other ends in view, which will readily appear as the nature of the invention is better understood, the same consists in the improved construction and novel arrangement and combination of parts, which will be 15 hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications to which recourse may be had within 25 the scope of the invention and without departing from the spirit or sacrificing the efficiency of the same.

In said drawings, Figure 1 is a side elevation, with part of the casing removed, of an instantaneously steam-generator constructed in accordance with the principles of the invention. Fig. 2 is a sectional elevation of the same. Fig. 3 is a horizontal sectional view taken on the line 3 3 in Fig. 1. Fig. 4 is a 30 perspective detail view of the connecting-frame for the generator-coils. Fig. 5 is a sectional detail view showing the union between two heating-tubes of different diameters.

Corresponding parts in the several figures 40 are indicated by like characters of reference.

The generator-tubes of the improved flasher are disposed within a casing C, which is preferably elongated or elliptical in horizontal section rather than circular, this shape being 45 preferred in order to enable a generator of considerable capacity to be stored in comparatively limited space—as, for instance, under the seat of an automobile—for the purpose of supplying motive power, to which 50 this improved device will be found to be particularly well adapted. The said casing may

consist of an outer shell 1, of sheet-steel, and a lining 2, likewise of sheet-steel, the space between the outer casing and the lining being packed with asbestos or other suitable non-conductive material, as shown at 3. In the lower part of the casing has been shown heating means (illustrated as a burner 4) of any suitable construction. It will of course be understood that heating means of any well-known kind whatsoever may be used in connection with the invention and that I do not consider myself as limited in this respect. The casing C is provided with openings, as 5, for the escape of products of combustion. 70

The generator proper is composed of a plurality of coils of tubing, preferably of the kind which is known as "Shelby" steel tubing, and in the construction of the device tubing of different sizes will be employed. In 75 the form of embodiment of the invention herein shown tubing of three different sizes has been employed; but within the scope of the invention any number of different sizes above two may be employed, and the relative proportions may be other than those which will be now described, the description applying particularly to the form of invention herein illustrated. Beginning, then, at the upper end of the generator, I have shown ten coils, all of 80 which are made of what is known as "standard quarter-inch-iron-size tubing," five of said coils (designated 6) being oblong or elliptical in shape, while other five coils (designated 6^a) are spirals. In the present instance the uppermost coil is elliptical, and the elliptical and spiral coils alternate, so that the last of the 85 ten coils will be a spiral. The next five coils, which are designated 7 and 7^a, are of a larger size of tubing than the upper coils, being preferably of what is known as "three-eighth-inch-iron size." The uppermost elliptical coil 7 is coupled to the lowermost spiral coil 6^a, and the elliptical coils 7 and spiral coils 7^a are disposed alternately, as shown. A third 90 set of coils of a still larger size, being of one-half-inch-iron-size tubing, has been shown. Four of these coils have been shown, the elliptical coils being designated 8 and the spiral coils 8^a. The lowermost coil of the intermediate size being an ellipse, the uppermost coil of the larger size will be a spiral and the lowermost coil of the larger size will be an ellipse. The elliptical and the spiral coils of the several sizes are all made separate and are connected with each other by means of right and left threaded unions or couplings 9. Special 95 100 105 110

couplings 10, having right and left threaded openings of different diameters, but with threads of the same pitch, are employed for coupling together the coils made from tubing of different diameters. By this arrangement any one coil which may show signs of wear or of burning out may be removed and replaced by a new one, leaving the remainder of the generator intact. The terminal of the uppermost coil 6 is extended through the casing and is suitably connected with the feed-water supply. The terminal of the lowermost coil 8 is likewise extended through the casing and connected with the point where the steam developed in the generator is utilized.

The several coils constituting the generator-tubes are assembled by means of bolts 11, serving to connect a pair of spiders 12, said bolts and spiders constituting a frame which retains the several coils or tubing in a convenient and effective manner in proper relation to each other, while at the same time access may be had to any one of the coils by disassembling the frame. In assembling the parts the coils are strung upon the bolts, as will be readily understood by reference to the drawings.

It will be observed that the largest coils—that is, the coils composed of the largest-sized tubing—are disposed most closely adjacent to the heating means and are consequently exposed to the greatest degree of heat, while the coils composed of tubing of less cross-sectional area are placed more remotely from the heating means. A degree of heat will be maintained, however, which will cause the feed-water as it enters the smaller coils to be vaporized practically instantaneously, the steam expanding downwardly through the coils composed of tubing of greater cross-sectional area, where the steam becomes superheated prior to its passage to the point where it is to be utilized.

As will be seen from the foregoing description, this improved flasher or instantaneous steam-generator is simple in construction, and owing to the peculiar arrangement of the generator-coils herein described the operation will be found very effective. By alternating the elliptical and spiral coils a free draft is provided, while at the same time the greatest possible surface is exposed to the action of the flames. By gradually increasing the size of the pipes through which the steam passes ample allowance is made for the expansion of the steam, and the largest coils being disposed where the heat is greatest the steam will pass from the generator at the point where it is most intensely heated, and consequently most capable of producing power.

As hereinbefore stated, the number of the coils employed and the relative number and arrangement of the different-sized coils may be varied within the scope of the invention.

65 I also do not restrict myself as regards the

means for assembling the coils or for supporting the same within the casing or with regard to the exact shape or proportions of the individual coils. Thus, for instance, the coils which have been described as being of "spiral" shape might be elongated to a less extent than the coils which have been described as "elliptical." Under some conditions even the coils might all be of the same shape; but for reasons hereinbefore stated the construction and arrangement herein described is deemed advantageous and preferable.

The spiders 12 of the frame serving to connect the generator-coils have been shown as provided with coil-engaging hooks 15, adapted to engage the outermost coils, and thereby greatly assist in securing the said coils in the desired relative position.

Having thus described the invention, what is claimed is—

1. In a flasher, a plurality of coils for the generating and superheating of steam, the tubing of the superheating-coils being disposed nearest the source of heat and of greater cross-sectional area than that of the generating-coils.

2. In a flasher, a casing, heating means, and a plurality of coils for the generating and superheating of steam; the tubing of the superheating-coils being of greater cross-sectional area than that of the generating-coils; the coils of the largest tubing being disposed in closest proximity to and the coils of the smallest tubing most remotely from the heating means.

3. A steam-generator composed of groups of coils formed of tubing of different cross-sectional area; the tubing of the coils disposed most nearly to the point of introduction of feed-water and most distant from the source of heat being of the smallest relative cross-sectional area, while the tubing of the groups of coils more distant from the point of introduction of feed-water and nearer the source of heat are of relatively larger cross-sectional area; the tubing of the coils from which the steam escapes being nearest the source of heat and relatively the largest.

4. In a flasher, a plurality of groups of coils of tubing of gradually-increasing cross-sectional area from the point of introduction of feed-water, which is remote from the source of heat to the point of escape of steam which is closely adjacent to the source of heat.

5. In a flasher, a plurality of groups of coils of tubing, of gradually-increasing cross-sectional area from the point of introduction of feed-water to the point of escape of steam which is nearest the source of heat; each group being composed of elongated and approximately spiral coils arranged in alternate order; and unions detachably connecting the coils of adjacent groups.

6. In a flasher, a plurality of groups of coils of tubing of gradually-increasing cross-

- sectional area from the point of introduction of feed-water to the point of escape of steam which is nearest the source of heat; some of said coils being elongated and others approxi-
5 mately spiral, and said elongated and approxi-
mately spiral coils being disposed in alternate order; and unions detachably connecting the individual coils and the different-sized types of adjacent groups.
- 10 7. A plurality of coils for generating and superheating steam, and a connecting-frame

including spiders and bolts separably connecting said spiders; the latter being provided with hooks engaging and supporting the upper and lower coils. 15

In testimony that I claim the foregoing as my own I have hereto affixed my signature in the presence of two witnesses.

FRANKLIN PIERCE HUMMEL.
